UNITED STATES PATENT OFFICE.

ALFRED T. BAXTER, OF NEW YORK, N. Y., ASSIGNOR TO NATIONAL
BLANK BOOK COMPANY, OF NEW YORK, N. Y.

TEMPORARY BINDER.

SPECIFICATION forming part of Letters Patent No. 764,413, dated July 5, 1904.

Application filed August 15, 1903. Serial No. 169,627. (No model.)

To all whom it may concern:

Be it known that I, ALFRED T. BAXTER, a citizen of the United States, and a resident of the city of New York, borough of Brooklyn, 5 in the county of Kings and State of New York, have invented a new and Improved Temporary Binder, of which the following is a full, clear, and exact description.

My invention relates to improvements in 10 devices for holding loose leaves or sheets in a secure manner, the same being commonly known as "temporary" binders.

The improvement which I have made is directed more particularly to the element known 15 in some classes of binders as the "post"—that is, the spindle or pin over which the leaves are slipped and on which they are held or confined usually by a locking-slat, which is adapted to have interlocking engagement with 20 the post at different points, according to the thickness of the mass of leaves.

The object that I have in view is to provide 25 an improved form of post capable of extension or prolongation on the gradual accumulation of the leaves, said post having its members interlocked and held in a secure positive manner and always presenting the ratchet-teeth on its several members in position for engagement with bolts or dogs on the locking-slat.

Further objects and advantages of the invention will appear in the course of the subjoined description, and the actual scope thereof will be defined by the annexed claims.

Reference is to be had to the accompanying 35 drawings, forming a part of this specification, in which similar characters of reference indicate corresponding parts in all the figures.

Figure 1 is a vertical sectional elevation 40 taken transversely through the temporary binder on the line 1 1 of Fig. 2 and illustrating my improvements. Fig. 2 is a horizontal sectional plan view in the plane of the dotted line 2 2 of Fig. 1. Fig. 3 is a vertical transverse 45 sectional elevation, the plane of the section being indicated by the dotted line 3 3 of Fig. 1, looking in the direction of the arrow; and Fig. 4 is a detail perspective view of one section of the extensible post.

As is usual in the art, the temporary binder 50 is provided with outside covers A A', each of which has a metallic reinforcement *a*, which is preferably connected flexibly thereto, as shown by Fig. 3. In some cases I provide the reinforcement *a* of the under cover A with a metallic strip or plate *b*, to which are secured the lower members B of two extensible posts, the latter being shown more particularly by Figs. 1 and 2. This lower member of each post is secured to the plate *b* by riveting said post 60 member thereto, although the post member may be attached in a permanent manner to the cover A by any other suitable means. This member B of the post is hollow or provided with a longitudinal passage *b'*, and the 65 upper end of said member is provided with a dovetailed tenon *c*, said tenon being arranged centrally with respect to the post member and providing shoulders on opposite sides of said post member. 70

Each post may consist of two or more members, such as C D E. The members C and D of the post are complements one of the other, each of said members having a dovetailed recess *d* at one end and the dovetailed tenon *c* 75 at the other end. The parts may be assembled for the tenon of one member to enter the recess of the other member, so as to secure the desired interlocking of the members one to the other endwise in series, thereby preventing 80 separation of the several members in an endwise direction. The upper member E of the post is provided at its lower end with a dovetailed groove *d*, which may have interlocking engagement with the dovetailed tenon 85 on either of the other members B, C, and D of the post, according to the number of leaves which are to be contained in the binder. It is evident that if a small number of leaves are to be used the post members C D may be omitted 90 and the member E may be interlocked directly with the member B; but as the number of leaves increase the members C and D are added successively to the member B and to one another, in which case the member E is coupled to the members C or D, as the case 95 may be.

The members C, D, and E are hollow or

provided with longitudinal passages similar to the passage b' , and these passages of the several members are adapted to receive the internal locking-pins F G, as shown by Fig. 1. 5 The locking-pin F is adapted to be slipped into the members B and C of the post in a way to prevent lateral separation of the tenons from the grooved ends of said members; but the locking-pin G is adapted to enter the 10 members D E of the post and to have locking engagement with the member E and with the upper cover A'. This locking-pin G is provided with an enlarged and male-threaded portion g and with a head g' . The upper 15 member E is provided with a reduced upper extremity e , forming an annular shoulder e' , said reduced end being thrust through an opening a' , which is provided in the metallic plate of the cover A'. The post member E 20 is provided in its reduced end portion e with a female thread, and when the pin G is thrust into the members E D said pin may have its threaded portion g screwed into the female-threaded portion e of the post member E, 25 whereby the head g' of said pin is adapted to bear on the outside upper cover A' in a way to bind the cover firmly to the upper ends of the posts.

It will be seen that the locking-pins F G 30 pass through the several members of the post in a way to prevent them from moving laterally one upon the other, and thereby confine the post members in their alined relation. If it is desired to shorten the post, the pin G 35 is removed by unscrewing it from the member E, after which the cover A' may be disconnected and one or more of the members C D E may be removed. If a short post is desired, the pin F is removed and the member 40 E is coupled directly to the member B, after which the pin G is inserted in order to attach the cover A' to the short post and to retain the members B and E in operative relation. If the size of the book increases, the member 45 C may be coupled to the members B and E, and the pin G is used to hold the members in position and to attach the cover A' to the post.

I prefer to employ two posts constructed 50 as just described in the binder, and these sectional posts are provided on their opposing faces with the series of ratchet-teeth indicated at h , each member of the post having a number of said ratchet-teeth. The tenons and 55 grooves are provided in the members of the post, so that the ratchet-teeth will take the proper positions when the post members are coupled together by fitting the tenon of one post member in the groove of the other post 60 member, thus insuring precision and certainty in the assemblage of the parts comprising the posts.

As is usual in some classes of binders, the posts support a locking-slat I, which is fitted

slidably over the posts and is adapted to rest 65 upon the group of leaves contained in the binder. This locking-slat is provided with suitable devices adapted to have engagement with the ratchet-teeth h of the posts in a way to prevent the slat from lifting under the resistance of the leaves. In Fig. 2 I have shown a suitable form of locking mechanism adapted 70 to be carried by the slat I, and in this figure the slat is shown as being of hollowed or chambered construction for the accommodation of 75 bolts J. The bolts are confined for sliding movement within the chambered slat by suitable devices, and they are normally impelled in opposite directions by springs j . The free 80 ends of the bolts are presented for engagement with the teeth of the ratchets h on the two posts, and the inner ends of said bolts have overlapping relation to allow a key to have engagement therewith for the purpose of retracting the bolts simultaneously from engagement with said ratchets of the posts. 85

Having thus described my invention, I claim as new and desire to secure by Letters Patent—

1. In a temporary binder, an extensible post consisting of sections provided with tenoned and grooved ends adapted for interlocking engagement, and means for holding the members against lateral separation. 90

2. In a temporary binder, a sectional post consisting of hollow members, one member being provided with a dovetailed tenon and the other member having a dovetailed groove adapted to receive said tenon and to have interlocking engagement therewith to hold said members against endwise separation, and 95 means within the hollow members for confining the members against lateral separation. 100

3. In a temporary binder, a sectional post having hollow members each provided with a series of ratchet-teeth, one of said members being provided with a dovetailed tenon and the other with a dovetailed groove, and a pin insertible in said hollow members for holding 105 them against lateral separation.

4. In a temporary binder, a sectional post having its members provided with ratchet-teeth, two or more of said members having dovetailed tenons and dovetailed grooves, and a locking-pin insertible in the members of the post and adapted to have interlocking engagement with one of said members. 110

5. In a temporary binder, the combination with leaves, of post members attached to one of the covers and provided with dovetailed tenons, other post members having ratchet-teeth along one side and grooved and tenoned ends interlocked with the first-named post members, and threaded pins screwed into upper post members and confining an upper cover thereon. 120

6. In a temporary binder, a separable post having a plurality of members coupled at their ends by interlocking tongue-and-groove joints 125

and held thereby against separation endwise, and means extending across the joints between the members for confining them against lateral separation.

5 7. In a temporary binder, a separable post having a plurality of hollow members coupled endwise by interlocking tongue-and-groove joints, and pins insertible in said members and extending across the joints between them for holding the members against lateral separation.

8. In a temporary binder, a separable post having a plurality of hollow members coupled endwise by interlocking joints, suitable covers to which the end members are fitted, and a headed screw having threaded engagement with one member of the post and clamping the cover firmly to said post, said screw ex-

tending into the separable post and across the joint between the members of said post. 20

9. In a temporary binder, suitable covers, a separable ratchet-post having hollow members coupled endwise by interlocking joints, one member of the post being fixed to one cover and another post member fitted to the other cover, and a screw threaded into a post member and clamping the cover thereto, said screw extending into the hollow post and across the joint between the members thereof.

In testimony whereof I have signed my name 30 to this specification in the presence of two subscribing witnesses.

ALFRED T. BAXTER.
